by his Atty Henry Marsh Jr.

UNITED STATES PATENT OFFICE.

THOMAS J. PAIRPOINT, OF PROVIDENCE, RHODE ISLAND.

DESIGN FOR A STATUETTE.

Specification forming part of Design No. **7,903**, dated November 24, 1874; application filed November 14, 1874.
[Term of Patent 7 years.]

To all whom it may concern:

Be it known that I, THOMAS J. PAIRPOINT, of the city and county of Providence, in the State of Rhode Island, have invented a new and original Design for Statuette, of which the following is a specification:

The nature of my design is fully represented in the accompanying photographic illustration, reference to which is hereby made.

A represents the figure of a stag, and B an overhanging crag. The stag is represented as standing upon the alert, with head erect and intensely watching some object in the distance.

I prefer to cast the statuette in bronze, but I do not consider the material in which it is formed to be an essential element of my design.

What I claim as my invention is—

The design for a statuette, substantially as described and shown.

THOMAS J. PAIRPOINT.
